UNITED STATES PATENT OFFICE.

GEORGE M. WELLS, OF BOSTON, MASSACHUSETTS, ASSIGNOR TO THE
SOLIDITY IRON LAST COMPANY, OF NEW YORK, N. Y.

LAST.

SPECIFICATION forming part of Letters Patent No. 288,286, dated November 13, 1883.

Application filed May 11, 1881. (No model.)

To all whom it may concern:

Be it known that I, GEORGE M. WELLS, of Boston, in the county of Suffolk and State of Massachusetts, have invented certain new and useful Improvements in Lasts, of which the following is a full, clear, concise, and exact description, reference being had to the accompanying drawings, forming a part hereof, in which—

10 Figure 1 is a lengthwise section of a last and socket embodying my invention. Fig. 2 is a section on line $x-x$, Fig. 1. Fig. 3 is a plan of the block from the under side.

My invention relates to that class of lasts 15 described in my Patent No. 223,263, dated January 6, 1880; and it consists, mainly, in holding the block B to the body A of the last by means of a tongue, a, on the block and a groove, b, in the body of the last, instead of 20 having the tongue in the body and the groove on the block, as heretofore in metal lasts.

When the groove is in the block and the tongue on the body, a core is essential in casting the block in order to form the groove; and 25 I have succeeded in dispensing with this core by forming the tongue upon the block and the groove on the body of the last. This is a very great practical advantage, as it cheapens the cost and also makes a better last. A spring 30 may be used with a plane tongue and groove, in order to prevent the block from dropping off; or the tongue and groove may be dovetailed, as shown.

In casting the last the block is cast first, 35 and one of the cast blocks is applied to the pattern of the body, the body-pattern and block being used for a pattern, the block being left in the mold when the body-pattern is drawn, so that the tongue upon the block 40 forms the groove in the body. The tongue is widest at the heel end and narrowest at the toe end, instead of widest at the toe end and narrowest at the heel end, as in all other cast lasts known to me.

45 Another very important advantage of this feature of my invention is that the fit of the tongue in the groove is far closer and better in my improved last than it can be made in cast-metal lasts when the tongue is on the 50 body and the groove in the block. The rea-

son of this is that it is not practicable to cast the block on the body, but the body must, for certain practical reasons well understood by all skilled in the art, be cast upon the block.

Now, if the body be cast upon the block 55 with a groove in the block, the metal forming the tongue in the body fills the groove in the block, and in cooling shrinks, and therefore makes a loose fit; but in my cast-metal last the fluid metal forming the body flows about 60 the tongue on the block, and in cooling the bulk of the metal forming the body shrinks in such a way as to bring the side walls of the groove closer together, thereby making a very 65 close and perfect fit between the tongue and groove.

I am aware of United States Patent No. 82,951 to Benjamin Hitchings, showing a wooden last with a tongue on the block and a groove in the body; and I disclaim this feature, except in lasts of cast metal, and except 70 when the tongue tapers toward the toe, and the groove tapers also in the same way.

Another feature of my invention consists in arranging the block B and stem D so that 75 when the stem is inserted in its socket S the heel end of the block shall rest against the outer surface of the socket, or against a spring, S', attached to the socket, thereby locking the block firmly in its place.

80 Another feature of my invention relates to the sole of the last, and consists in forming a ridge, R, parallel with the edge of the last. This ridge is for the purpose of bringing the force of the blow of the hand-hammer or the 85 compressing action of the nailing or pegging machine more directly along the line of the nails or pegs, and thereby settling the stock more perfectly. This ridge, in lasts on which 90 shoes are to be nailed, should extend clear around the sole, but is more desirable at the ball or fore part than at any other part of the last. Another advantage of this ridge is that when roughened by use it can be readily smoothed off.

95 What I claim is—

1. In a cast-metal last, the block B, provided with tongue a, widest near the heel end and growing gradually narrower toward the toe, in combination with body A, having a groove, 100

b, corresponding with tongue *a*, that is widest at the heel end and growing gradually narrower toward the toe, as described.

2. A metal last having a ridge, *R*, on the sole parallel with the sole-edge, substantially as and for the purpose set forth.

3. In a last, the combination of socket *S*, stem *D*, and block *B*, as set forth, and means,

substantially as described, whereby the block *B* is locked when the last is in the socket, substantially as described.

GEO. M. WELLS.
